ABSTRACT

A frame is set on a roll-line on which the material to be marked is transported; a marking machine is mounted on a beam of said frame; said machine rapidly and automatically selects position of setting mark or selects type at each marking time, arranging in a straight line on the marking roll the marking punch for the numbers, letters, figures, etc. to be marked. When the material is transported on said roll line, the marking roll comes down while rolling on said material as being transported and completes marking without any obstacles such as stop of the transportation of the material or reduction of the velocity thereof; after finishing marking, the marking roll automatically returns to the original position on the frame. Automatic marking can thus be effected on the material as being transported.

ROLLING-TYPE MARKING MACHINE

BACKGROUND OF THE INVENTION

This invention relates to a rolling-type marking machine and a method for automatically marking a traveling material by the use of said machine.

Marking machines which heretofore have been used generally are of such structure that a plurality of punches are manually set on the marking part so that said punches may strike vertically a predetermined position of the material by means of a hammer and the like.

Accordingly, such machines have disadvantages that the punches are apt to be worn out by vibration of the strike so rapidly that punch life will be shortened, and that the material is brought into slip contact with the punches which results in occurrence of the so-called marking slip. Moreover, the conventional machine needs a great deal of labor for type-selection, type-setting of parts of punch or removal of the same and marking. Also, since the material is marked under quiet conditions, the material such as steel sheets or plates ready for marking generally are stored in a yard, which gives rise to decrease in the utility of the space of such factory as inasmuch as the material or the marking machine must be carried to the storage place.

This invention overcomes the afore-said disadvantages which have been encountered in the conventional machine or method.

SUMMARY OF THE INVENTION

This invention is directed to a rolling-type marking machine which comprises type-selecting ring gears, marking punches each having a curved surface as a marking surface which is smaller than that of said type-selecting ring gears, a hole pierced from the outer periphery to the inner surface of each tooth of said gears for inserting said punches therein, a pin inserted through a bore pierced through each tooth and punch, a spindle or center shaft on which ring gears are fitted, the number of rings being equal to the number of the figures to be marked, a locking member adapted for travelling in and out along a groove in the center shaft in the direction of the axis of the outer surface of said center shaft and in a notched groove at the inner surface of each of said gears so as to set said ring gears rotatably and also to lock the same in alignment, a rotatable shaft extended eccentrically and outwardly from both sides of said center shaft so as to rotate eccentrically said center shaft, pinch rolls for grasping a group of said gears eccentrically whereby one row of the marking punches is projected from the circumferential surface, a one position clutch, brake mechanism, a driving machine and a control mechanism for stopping said rotatable shaft at a predetermined angle, a number of rack bars meshing with said group of gears to rotate the same individually, said number of rack bars being the same as that of said gears, rows of fluid cylinders provided on the opposite side of the stand common with said row of rack bars, the tip ends of said cylinders being connected to respective rack bars and capable of travelling in the forward or reversed direction and by the distance enough to rotate a gear or ring a predetermined number of teeth, a means to release and reset the engagement of said rack bars and the gears so as to shorten the length of the groups of said rack bars and said cylinder, and a means to detect erroneous opera-

tion by signalling the degree of movement of said rack bar as a number of pulses. The present invention also concerns an automatic control means to receive, as input, the characters, numbers, figures, etc. to be marked 5 subsequently and operate the fluid cylinder to automatically select types for the row of the marking punch to be marked; a means to measure the thickness of the material plate being transported so as to detect the height of the marking surface to be marked whereby 10 the height of the marking machine is automatically controlled; and a method for automatically marking the material by virtue of the operation of automatic control means wherein the circumference of the constant angle of the pinch roll, the distance between the position of 15 the marking roll and that of a means to detect the time of pass of the tip end of the material and the distance between the tip end of the material and a plurality of marking positions are received as input.

1. The first feature of this invention is that a marking 20 machine is provided with a rolling-type marking roll having a round bar center shaft piercing a plurality of type-selecting ring gears such ring gears being idly mounted on said center shaft, and a rotatable shaft eccentrically extended from both sides of said center shaft.

2. The second feature of this invention is that the 25 marking machine according to the item 1 is provided with the rolling-type marking roll in which the rotatable shaft has pinch rolls for an assembly of said ring gears and only one row of marking punches thereof is projected from the peripheral surface of said pinch rolls.

3. The third feature of this invention is that in the 30 marking machine according to the item 1, the plurality 35 of the ring gears pierced by the center shaft is composed of a plurality of ring gears of the same shape, and the marking punches are fixed on the tip of the teeth thereof.

4. The fourth feature of this invention is that in the 40 marking machine according to the item 3, holes are provided through the teeth of said gears in the direction of the diameter thereof, and the marking punches are inserted through said holes such that the base ends thereof abut and rest upon the center shaft.

5. The fifth feature of this invention is that in the 45 marking machine according to the item 4, bores are provided through the marking punches and the side wall of the teeth of said ring gears, through which pins are inserted to fix the marking punches.

6. The sixth feature of this invention is that in the 50 marking machine according to the item 5, the marking surface on the rolling side of the marking punch is shaped such that it is a curved surface having a smaller radius than that of the rotatable roll which supports said punch.

7. The seventh feature of this invention is that in the 55 marking machine according to the item 1, a groove is provided (in the axial direction) on the outer surface 60 of said center shaft; two outer shoulders of a locking member which moves in and out of the groove at said outer surface of said center shaft along two side walls and the bottom wall of said groove are shaped so as to have slopes or oblique surfaces; and said oblique surfaces abut on two oblique surfaces of a groove provided 65 on the inner circumferential surface of the ring gears so that said ring gears are locked and placed in alignment on the center shaft.

8. The eighth feature of this invention is that the marking machine according to the item 1 is provided with a primary one-position clutch idly fitted to said rotatable shaft and having teeth of a worm wheel on the outer circumferential surface, a secondary one-position clutch inserted through the spline of said rotatable shaft and capable of sliding only in the direction of the axis of said shaft, a worm meshing with said worm wheel for positioning said one-position clutch after rotation of a desired angle whereby the rotation of said clutch is locked, brake means to control the rotation of said rotatable shaft, control means to open or close the operation circuits for the primary one-position clutch and the brake means respectively, and a means to give instructions about the operation of said control means.

9. The ninth feature of this invention is that the marking machine according to the item 8 has, as the one position clutch, a disc clutch wherein at least one ring-like protrusion is provided on the opposite surface and in a part of said ring-like protrusion, a protrusion and a recess which are engaged with each other are provided in the primary side and the secondary side and also means is provided to resiliently push the primary side and the secondary side under pressure.

10. The tenth feature of this invention is that in the marking machine according to the item 3, a plurality of rack bars meshing with each type-selecting ring gear and slidably supported by a stand are provided so as to individually rotate the ring gears and arrange the marking punches to be used in a line of axial direction and means is provided to effect individual sliding movement of said rack bars.

11. The eleventh feature of this invention is that in the marking machine according to the item 10, control means is provided wherein each of said rack bars is connected to the extended end of a plurality of fluid cylinders connected in series, and the required number of cylinders are selected therefrom and caused to operate simultaneously.

12. The twelfth feature of this invention is that the marking machine according to the item 10 is provided with rack bars each having teeth more than half of those of the type-selecting ring gear, means to cause or release the meshing of the type-selecting ring gears with the rack bars, movement means to allow said rack bars to move in forward and reverse directions, and automatic control means to give the movement means the instructions to arrange said rack bars in the position suitable for the next rotation of said ring gears.

13. The thirteenth feature of this invention is that in the marking machine according to the item 12, the base ends of the cylinders are fixed to a beam standing on the upper surface of the stand and are placed zigzag, each staggered by half the plane width, the ring gears are pierced by, and fitted around, the round bar center shaft arranged along the axial line of said beam below the stand, the row of the rack bars meshing with the row of said ring gears is mounted on a guide roller and supported by an arm, and the ends of the piston rods of said cylinders and the ends of said rack bars are connected by connecting means through said stand.

14. The fourteenth feature of this invention is that in the marking machine according to the item 13, a plurality of dovetail grooves are provided on the common stand for said cylinders and said rack bars, protrusions are provided on each side of said connecting means,

and each said protrusion is adapted to be fitted into each said dovetail groove.

15. The fifteenth feature of this invention is that in the marking machine according to the item 12, the type-selecting means which selects the characters and figures, etc. of the marking punches set on the teeth thereof meshing with the racks by the movement of the rack bars caused by the stroke of the cylinders, is provided with an automatic control means for the type-selecting means which comprises a preset storage part for marking a given preset value A from the next preset value C and storing the same with the preceding preset value B, a comparing arithmetic circuit which compares the present preset value A with the preceding preset value B so as to calculate the value by which the ring gear should be rotated to right or left within the range less than half of the number of the teeth and the direction in which the rack bar should be moved and reset by the distance corresponding to half of the number of the teeth of the ring gear and stores the same, an output circuit to convert the code into the normal figures and amplify the same for driving, driving means to open an instructed electromagnetic valve to move the cylinder so that the rack bar may be moved to right or left by the distance as instructed, and means for detecting any erroneous operation to compare the amount of movement of the rack bar sent from means for detecting the amount of the movement of the rack bar with the instruction figures sent from the comparing arithmetic circuit and give instructions about any appropriate action needed based upon the existence of any such erroneous operation.

16. The sixteenth feature of this invention is that any of the marking machines according to the items 2 to 15 is mounted on a beam of a frame set on the transportation line of the material to be marked; the marking punches to mark with are placed in a line with the selected types; when the material to be marked is transported on the line, the marking roll comes down toward the material according to the instruction of the control means and the pinch rolls are at first brought into contact with the surface of the material and caused to roll on it as the material proceeds; the center shaft piercing the ring gears and eccentrically connected to said pinch rolls is also caused to roll; the row of the marking punches set in a line reaches the lowest position, projecting beyond the plane of the pinch rolls and completes marking; when the material proceeds farther, the center shaft is also caused to roll farther so that the row of the marking punches is retracted inside the plane of the pinch rolls, ascending to the original position according to the instructions of the control means; the marking punches with the next types to be marked with are placed in a line for repeated operations; and thus the marking is effected without stopping the material.

17. The seventeenth feature of this invention is that in a method according to the item 16, there is provided an automatic control apparatus for determining the height of the marking machine comprising; means to detect height of the position of the marking machine, means to convert said height into signals, means to preset the thickness of the material plate to be marked, means to convert said thickness into signals, means to compare and calculate said two signals received as input and thereby give instructions about the next position of the marking machine, a control panel to control

motor velocity, a motor for presetting the next position of the marking machine, and means to supply electric power or pressurized fluid to said motor.

18. The eighteenth feature of this invention is that in a method according to the item 16, there is provided an automatic control apparatus for the marking position comprising: means to generate a signal informing that the tip of the material has passed the area apart by a preset distance from the marking machine, means to generate pulse for each predetermined length of the circumference of the line roll as it rotates, control means to store a plurality of values obtained by subtracting half of the circumference of the pinch roll of the marking machine from the sum of said preset distance plus the distance between the tip of the material and the marking position, calculating the number of said pulses from the time when said signal is received to thereby give instructions about start of the marking machine at each said calculation, and a fluid cylinder to be started according to said instructions so as to push the pinch rolls to the surface of the material to be marked.

As set forth hereinabove, this invention has many advantages whereby automatic type-selection of the marking punches can be effected rapidly and accurately. Particularly, since the marking operation can be conducted automatically by means of rotation of the marking roll over the entire length of the material as being transported without stop of the travel thereof, the marking punches are not subjected to vibration shock, thus having a long life and there is no fear of marking-slip occurring on the material. Moreover, since the type-selection and marking operation can be done automatically, a great deal of labor can be saved and the floor space for marking is not substantially required, which results in smaller factory space and yet more products shipped therefrom.

BRIEF DESCRIPTION OF THE DRAWINGS

The invention will appear more clearly from the following detailed description taken in conjunction with the accompanying drawing in which:

FIG. 1 is a front elevational view, partly in section of a marking roll of a type with which the present invention is concerned.

FIG. 2 is a view on an enlarged scale of the marking roll shown in FIG. 1, the pinch rolls of the marking roll being shown in contact with a plate to be marked.

FIG. 3 is a view of one of the ring gears embodied in the marking roll.

FIG. 4 is a sectional view as taken along the line IV-IV in FIG. 3.

FIG. 5 is a perspective view of a pin used to secure the marking punches in the teeth of the ring gear depicted in FIG. 3.

FIG. 6 is a fragmentary plan view depicting a condition of poor marking on a steel plate as effected with prior art devices and techniques.

FIG. 7 is a fragmentary plan view depicting the uniform clear marking of a steel plate possible with the marking roll of the present invention.

FIG. 8 is a side view of a marking punch as embodied in the marking roll of the present invention, showing the curvature of the marking tip end thereof as provided in accordance with the principles of the present invention.

FIG. 9 is a longitudinal sectional view of the marking roll provided by the present invention showing the embodiment of locking means therein to align and lock the respective ring gears to the center shaft during the marking operation.

FIG. 10 is a transverse view through FIG. 9, the ring gears being locked to the center shaft.

FIG. 11 is a fragmentary view on an enlarged scale of a portion of the marking roll shown in FIG. 10, the locking means being shown in released condition.

FIG. 12 is a schematic view of apparatus for stopping the marking roll at a desired angular position.

FIG. 13 is a side elevational view of a one-position clutch used in the apparatus of the present invention and particularly in the apparatus depicted in FIG. 12, the clutch being shown in released condition.

FIG. 14 is a side elevational view of the clutch shown in FIG. 13 in engaged position.

FIGS. 15a and 15b are, respectively, views of further constructional features of the one-position clutch.

FIG. 16 is a side view partly in section of the clutch showing the mounting thereof on the rotatable shaft associated with the marking roll.

FIG. 17 is a side view in elevation of the marking roll of the present invention along with the automatic type selecting devices associated therewith.

FIG. 18 is generally similar to FIG. 17 except the apparatus is shown on an enlarged scale.

FIGS. 19 and 20 are, respectively, side elevational and plan views of a further embodiment of the apparatus of the present invention.

FIG. 21 is a side elevational view of type selecting apparatus in accordance with the present invention which is adapted to prevent the apparatus from swinging up and down during the operation thereof in such manner as would cause vibration and consequent damage thereto.

FIG. 22 is a sectional view as taken along the line 40 M-M in FIG. 21.

FIG. 23 is a sectional view taken along the line L-L in FIG. 21.

FIGS. 24a and 24b are block diagrams of automatic control apparatus used by controlling the operation of 45 the type selecting and marking apparatus of the present invention.

FIG. 25 is a block diagram of automatic control apparatus for determining the height of the marking apparatus relative to the material being marked.

FIG. 26 is a side elevational view depicting the manner in which the marking roll of the present invention is operated to effect marking of a moving steel plate.

FIG. 27 is a block diagram showing automatic control apparatus associated with determination of the marking position.

FIG. 28 is a side elevational view showing the manner in which the apparatus in FIG. 27 is used in conjunction with determining the marking distance.

FIG. 29 is an elevational view of the manner in which the marking roll and apparatus of the present invention can be employed in a mill in conjunction with a plate transporter unit and mounting structure for the marking roll to facilitate the marking operation.

FIG. 30 is an elevational view of an enlarged scale of a portion of the apparatus depicted in FIG. 29.

FIG. 31 is a side elevational view of the apparatus depicted in FIGS. 29 and 30.

Detailed description of the preferred embodiment

FIG. 1 is a schematic side view for describing the principle of the marking roll of this invention in which the reference numeral 1 is a type-selecting ring, 2 is a marking punch, 3 is a round bar center shaft piercing a plurality of the rings 1, the rings being loose on shaft 3, 4 is a rotatable shaft extended eccentrically and, longitudinally from the opposite ends of center shaft 3, 5 is a bearing of the rotatable shaft 4, the line X—X is the axis of the shaft 3, the line Y—Y is the axis of the shaft 4, said line X—X being eccentric to line Y—Y by δ , and 6 is a housing for the bearing 5.

In order to mark the material by the use of the marking roll of the invention, all the typeselecting rings 1 are at first released from engagement with the shaft 3 so that it can rotate freely. Then each ring 1 is rotated so that the desired numbers or figures may be arranged in a desired line of punch indicia. Thereafter all the rings 1 are placed into fixed engagement with the shaft 3. When the location on the plate at which marking is to be effected thereto, approaches the marking position by substantially one-half of the circumference of a circle circumscribing the outermost edge of the rings 1 with the axis Y—Y as the center, the shaft 4 is caused to start and the travelling direction and the velocity of said circle is caused to synchronize with the movement of said material. Since the center shaft 3 is eccentric to the shaft 4, the row of the punches in said upper line comes down as it rotates and said outermost edge of the rings comes into contact with the surface of the material. The row of the punches which projects from the outermost edge enters inside the material to effect marking. Since the surface of the marking punches is then rotating in synchronization with the movement of the material, such surface is not subjected to stress in the direction of the travel of the material, gradually entering into and gradually going out of the material as the punch surface rotates. The pushing force of the marking punches are thus not focused on one instant but rather dispersed over some length of time though short, which makes it possible to use a smaller pushing force with lesser amount of wear of the punches with the letters and the figures marked therewith being uniform and clear.

FIG. 2 is a modification of FIG. 1 wherein a pair of pinch rolls 7 each having a diameter which is 2δ larger than that of the type-selecting ring 1 are fixed to the shaft 4 so as to grasp a group of the rings 1. Since the diameter of the pinch rolls 7 is 2δ larger than that of the ring 1 and the axis X—X of the shaft 3 mounting the rings 1 is eccentric by δ to the axis Y—Y of the shaft 4, the pinch rolls 7 are positioned in the same line with the rings 1 at one intersection with a plane including the axes X—X and Y—Y while the pinch rolls 7 are positioned 2δ outside from the rings 1 at another intersection with said plane.

Accordingly, in case of FIG. 1, it is difficult to eradicate erroneous actions with respect to the driving velocity of the shaft 4 and the presetting of the height of the material even if they are accurately controlled. In case of FIG. 2, however, if the marking roll is only allowed to come down into contact with the surface of the material 8, the pinch rolls 7 can automatically mark the surface of the material 8 while rolling thereon by virtue of the contact friction between the pinch rolls 7 and the material 8, which results in omission of the

driving force upon the shaft 4 as well as elimination of the erroneous actions.

FIG. 3 is an elevational sectional view for explaining the structure of the type-selecting rings in the rolling-type marking roll of this invention, and FIG. 4 is a sectional side view thereof.

The conventional type-selecting ring has on its side a gear for rotation for the purpose of type-selection. Therefore, the marking punches cannot be placed in access to one another, so that the mark obtained is apt to be lengthened as compared with that manually obtained. For example, with the letters of 7 mm $\times$ 10 mm, the interval may usually become 40 mm or so. Consequently, the mark has a bad appearance, is difficult to read, occupies a larger soiled area on the material, necessitates a larger marking roll and requires more power to effect marking.

In this invention, the type-selecting ring itself is shaped as a ring gear so that it has also a function of the conventional gear for rotation, and is provided with holes extending radially in each tooth, in which each marking punch is received.

In this invention, therefore, the intervals between respective adjacent punches can be shortened as is the case with the manual marking, and the direction of the marking punches and the depth of marking can be arranged uniformly. Accordingly, it has many advantages that the mark obtained has good appearance, the spoiled area by marking can be decreased, and the marking machine can be of a smaller size and weight.

When the punches are received through the holes of the ring gear teeth, it has heretofore been a practice to protrude the upper side or the middle part of the marking punch laterally so as to thereby bear the load of the marking surface. As a result, the manufacture of the punches has been made, complicated and difficult. Moreover, the resisting power to the pressure has been insufficient and the punch has sunk at the time of marking, which results in irregular marking on the material. For instance, in case of effecting marking of a number of 20 figures on a steel plate, an allowable range of the punch depth to maintain good appearance is 0.15 mm or less. However, it is impossible in the above conventional method to observe said range.

In this invention, a hole is provided through each tooth of the ring gear in the direction of its diameter, through which hole the marking punch 2 is inserted so that the base end thereof may abut and rest upon the center shaft 3.

In this invention, the body of the punch 2 and the hole through which it is inserted are both straight, which makes the manufacture easy and accurate. Furthermore, the stress caused by marking is fully supported through the entire surface of the base end of the punch by the center shaft 3. Thus it makes it very easy to maintain the punch depth within 0.15 mm so that a very clear mark can be obtained on the material.

In the conventional method, the marking punch is inserted through a hole of the type-selecting ring and thereafter a taper pin, cotter pin or the like is struck into the gap therebetween so as to fix the punch in the hole of the ring. In this old practice, it is difficult to uniformly align the heads of the pins struck below the surface of the punches and maintain the uniform security thereof. It is more difficult to draw out said pins when it is desired to repair or change said pins. Also this practice is undesirable because the marking punch be-

comes offset from the center of the hole by the thickness of the pin.

On the contrary, this invention has a feature that there is a bore provided in both the marking punch and the side wall of the tooth of the ring gear, through which bore is inserted a pin to fix the punch in the tooth. Such a pin is shown in FIG. 5 as a bush 9 having a slit 10 in the axial direction. If such a bush is used as the pin, it is easy to insert the same through the bore and support the punch therein in view of its resiliency.

It has heretofore been a pre-requisite to shape the body of the marking punch and the ring gear hole through which said punch should be inserted as a square or a rectangle for the purpose of aligning the direction of the letters to be marked, which has made the working or manufacture thereof very difficult.

In this invention, however, the direction of the letters to be marked can be determined by means of the pin 9. Thus it is not always necessary to shape the body of the punch and the hole therefor into a square or rectangle, which may thus be round or other desired shape. As a result, the cost therefor can be largely kept down.

Conventionally, the marking process by the use of the punch has been effected under stop conditions, whereby when the marking surface of the punch is a plane perpendicular to the axis of the punch, the letters, fingers, etc. on the marking surface can be marked with uniform clearness. However, as to the form of the marking surface in case that the marking process is conducted while the material being marked is rolling, there is no known teaching.

According to our experiments, it has now been found that when the marking surfaces of the punches formed into planes perpendicular to the respective axes are positioned in a line and caused to mark the material while rolling, both sides of the letters can clearly be marked but the middle part thereof is not clear and difficult to read, as shown in FIG. 6. In order to overcome this disadvantage, various studies have been made and it has been found that if the marking surface 11 in the direction of rolling of the marking punch 2 is shaped as a curved surface having a radius γ smaller than the rolling radius R of the marking roll 1 as shown in FIG. 8, all letters, figures, etc. can be clearly marked as shown in FIG. 7.

FIGS. 9 to 11 illustrate one embodiment of a locking means to align and lock the type-selecting ring 1 with the center shaft 3 in the rolling type marking roll of this invention, in which FIG. 9 is a longitudinal sectional view thereof, FIG. 10 is a transverse sectional view thereof with one ring gear being shown in full lines, and FIG. 11 is a partial enlarged view of FIG. 10.

As seen from FIGS. 9-11, a groove 12 is provided on the outer surface of the shaft 3 extending in its axial direction the bottom wall 13 of the groove 12 being an oblique surface or slope and both side walls thereof are parallel planes perpendicular to the bottom wall 13. The type-selecting rings 1 which are overlapped and fitted around the center shaft 3 are provided with trapezoid notches 15 on the inner surface disposed centrally between two adjacent punches 2, the number of said notches being same as that of the punches 2. The locking member 16 is a rod-like member, its underside comprising a slope or an oblique surface 17 similar to the bottom wall 13 of said groove 12, its both sides being parallel planes to match with the side walls 14 of said groove 12 and its top side being of a trapezoidal

shape similar to the notch 15 on the inner surface of the ring 1. The member 16 is present in the groove 12 of the shaft 3. If it is pulled to the right in FIGS. 9 and 10, its underside slides up along the slope of the bottom wall 13 of the groove 12 and its top side having a trapezoidal shape enters and matches the shape of trapezoidal notch 15 of the ring 1 so that the ring 1 is aligned and locked with the shaft 3. Conversely, if the member 16 is pulled to the left, the underside 17 of the member 16 slides down along the slope of the bottom wall 13 of the groove 12 and the top side 18 of the member 16 is then sunk inside the peripheral surface of the shaft 3 to release locking of the ring 1 as shown in FIG. 11. Thus in the marking roll of this invention, after all type-selecting rings are released from locking engagement with the shaft 3 by pulling the locking member 16 to the left of FIG. 9, the respective rings 1 are caused to rotate so as to position the letters, figures, etc. to be marked in the uppermost line of the roll and then the member 16 is pulled to the right of FIG. 9 so that all rings 1 can be aligned and locked with the center shaft 3. Thus, even if there is any error or difference in the angle of the rings, accurate locking can be effected by the trapezoidal top part 18 of the material 16 entering into the notch 15 on the inner peripheral surface of the rings 1, and no error or mistake occurs after locking.

FIG. 12 is a schematic view of an example of apparatus to automatically stop the marking roll at any desired angle. It is characterized by having a primary one-position clutch 22 idly fitted on the shaft 4 and provided with the teeth of a worm wheel on its peripheral surface; a secondary one-position clutch 23 fitted to a spline shaft 31 as a part of the shaft 4 and slidable only in the axial direction of said shaft 4; a worm 21 meshing with the worm wheel of the clutch 22 so as to rotate it by a desired angle to a desired position and lock its rotation; brake means 20 to brake the rotation of the shaft 4; driving means 19 to drive the shaft 4, the rolling-type marking roll 30 to be driven by the shaft 4; control means 28 and 29 to open or close the operating circuitry of said primary one position clutch 22 and said brake means 20 respectively; and instruction means 26 to give instructions about opening and closing of said control means 28 and 29. The numeral 27 denotes control means to open or close the operation circuit of the driving means 19 according to the instructions of the means 26, and 24 and 25 denote sources of electric power.

Usually in the rolling-type marking roll, the row of punches to mark with is positioned in the uppermost line of the marking roll. According to the instructions for marking, the marking roll comes down into contact with the material to be marked and at the time when the pinch rolls 7 are caused to rotate by 180 degree the material is marked. The length thus corresponds to half the circumference of the pinch rolls 7. However, such length is not allowable in some material whereby it is sometimes required to effect marking at the time corresponding to half or two thirds of said length. In such case, the apparatus shown in FIG. 12 is actuated to set the row of the marking punches to be used for such marking at the position of 90° or 120° from the lowermost position of the pinch rolls. As described, the apparatus of FIG. 12 serves to allow the marking to take place at the time when the pinch rolls 7 roll by any desired angle after they come into contact with the surface of the material.

FIGS. 13 to 16 show the one position clutch to be used for the automatic stop apparatus at any desired angle of FIG. 12, in which FIG. 13 is a side view of the clutch under released conditions; FIG. 14 is a side view of the clutch under engagement conditions; FIG. 15 (a) and (b) are plan views showing the internal construction of the clutches; and FIG. 16 is a sectional view of the clutch fitted to the rotatable shaft.

In this example, the primary one-position clutch 32 has three-fold rings 34, which rings have the protrusions 35, each having interval of 120 degrees. The secondary one-position clutch 33 has three-fold rings 36 corresponding to said rings 34, which rings 36 have the recesses 37 to be engaged with said protrusions 35. When the primary clutch 32 brought into contact with the secondary clutch 33 is allowed to rotate, the former is engaged with the latter at only one point among 360 degree and in the other points the protrusions 35 are caused to slide on the rings 36. In order to relieve the shock and lessen the friction at contact, a ball spring 38 is provided, while in order to strengthen the engagement electromagnet 39 is provided.

Since this one position clutch is so constructed, it rotates without appreciable noise or shock when released, while it is firmly connected when engaged, so that it can bear a considerable load.

FIG. 17 illustrates a schematic side view for explaining the principle of the automatic type-selecting apparatus constituting one element of the rolling-type marking roll of this invention wherein 1 is a type-selecting ring gear; 2 is a marking punch fixed through each tooth of said gear; 3 is a round bar center gear; 40 is a rack bar meshing with said ring gear 1; 41 and 42 are arms provided with rolling axes and support said rack bar 40 slidably; 43 is a frame; 44 is a beam; 45, 46 and 47 are fluid cylinders; 48 is a piston rod for these cylinders; and 49 is connecting member to connect the tip of the piston rod and the rack bar 40.

These cylinders 45, 46 and 47 are arranged such that they automatically open or close a fluid valve according to the instructions and cause the piston to move in a moment over the entire length of the cylinder whereby the rack bar 40 connected via the means 49 is in turn caused to move to the right or left.

The entire travel due to the stroke of the cylinder 47 accurately corresponds to the rotation by one tooth of the ring 1, that of the cylinder 46 by two teeth and that of the cylinder 45 by three teeth of the ring 1. Therefore, when it is desired to rotate the ring 1 to the right or left by one tooth, all that should be done is to move the cylinder 47 to the right or left. Similarly, the cylinder 46 is moved for two teeth and the cylinder 45 for three teeth. When it is desired to rotate the ring 1 by 4 teeth, the cylinders 47 and 45 may be worked simultaneously; the cylinders 46 and 45 for 5 teeth; and the cylinders 47, 46 and 45 for 6 teeth.

In FIG. 17 the ring gear 1 is shown as having 10 teeth. Accordingly, in order to select types of 5 teeth of the right side on the uppermost position, the rack bar 40 is caused to move to the left so as to rotate the ring 1 by one tooth to five teeth in the anti-clock-wise direction. On the other hand, when it is desired to select types of 5 teeth of the left side on the uppermost position, the rack bar 40 is caused to move to the right so as to rotate the ring 1 by one tooth to five teeth in the clock-wise direction.

These type-selecting operations can be done instantly, automatically and accurately by opening or closing electromagnetic valves in the line concerned according to the instructions from the instruction means 26. The fluid cylinders are strong enough to meet the requirements of power for movement of the piston, piston rod, rack bar, type-selecting rings, etc. The figures of the number, etc. to be marked are usually 10 to 20. Each figure is constructed by one ring, each ring having its own automatic type-selecting apparatus as described above. According to the instructions from the instruction means 26, the type-selecting rings are caused to rotate simultaneously and complete selection of types in a moment.

FIG. 18 is a schematic view for further explaining the function of the apparatus of FIG. 17, in which the rack bar has moved to the right and placed the marking punch for the number 6 on the uppermost position. In this case, if the types to be used in the next marking operation are such numbers as 7 to 12 on the right side of FIG. 18, the rack bar can move to the left to select any number of said range and place the same on the uppermost position. However, if the types to be used next time are such numbers as 1 to 5 on the left side of FIG. 18, it is impossible to select such types or numbers since the rack bar 40 has no further teeth with which such bar can be moved to the right. In order to solve the problem, one end of the frame 43 is pivotally supported by a side stand 51 while the other end thereof is supported by a side stand 50 so that it may be lifted or lowered as desired. In this case, the stand 50 is elevated to lift the rack bar 40 so that the relation between the bar and the ring 1 is such as shown in long and short dashed lines whereby both are released from each other. The rack bar 40 can thus be moved to the left and then the stand 50 is lowered with the rack bar to reset the same with the ring 1, waiting for the next instruction.

The above described construction of this invention serves to save the entire travel of the strokes of cylinders 45, 46 and 47 and the entire length of the rack bar 40 to half of the same and also to facilitate acceleration of the marking roll in accordance with the velocity of the material being transported because the rack bar is set apart from the marking roll.

FIGS. 19 and 20 show a high density automatic type-selecting apparatus for the marking roll of this invention, in which FIG. 19 is a side view and FIG. 20 is a plan view thereof.

In the apparatus of this type, the cylinders 45, 46 and 47 have sections of square or rectangle different from the usual fluid cylinders. To one side of the beam 44 standing on the frame 43, the base ends of a group of cylinders are fixed, the number of said cylinders being equal to that of the type-selecting rings 1. To the other side of the beam 44 on the frame 43, the base ends of a group of cylinders 45', 46', 47' of similar shape are fixed whereby they are arranged zigzag, each staggered by half of the width of its lower side. The round bar center shaft 3 extending through and supporting an assembly of rings 1 is mounted on the underside of the frame 43 in the axial direction of the beam 44. Also on underside of the frame 43 a pair of arms 41 and 42 are fitted, by which the rack bars 40 and 40' are supported, said rack bars being positioned between the frame 43 and the center shaft 3, the bar 40 being connected to the connecting means 49 and the bar 40 connected to

the means 49', so that each bar may mesh with the ring 1. The conduct 53 and 53' for the pressurized fluid connected to both sides of each cylinder are connected to the electromagnetic valves 52 and 52', respectively. The numeral 54 denotes a stop to prevent the ring 1 from rotation when it is released from engagement with the bars 40 and 40'.

The width of the letters, figures, etc. of the marking punch is about 7 mm in most cases and it is thus advisable that the pitch of the ring should be about 15 mm. In case of arranging the cylinders so as to match with this pitch, the diameter of the cylinder must be made extremely small, which restricts the output to a very low value.

In this invention, the groups of cylinders are arranged zigzag on either side of the beam 44 so that the pitch is contracted by 50 percent and the width of the underside of the cylinder is allowed to be as far as about 22 mm, which results in increase in the capacity of the cylinder. In other words, the invention exemplified by FIGS. 19 and 20 make it possible to arrange the type-selecting cylinders very compactly without decreasing the capacity thereof.

The apparatus shown in FIGS. 21 to 23 is directed for preventing the type-selecting apparatus from swinging up and down during the operation, in which FIG. 21 is a side view, FIG. 22 is a sectional view taken along the line M—M of FIG. 21, and FIG. 23 is a sectional view taken along the line L—L of FIG. 21.

In the operation for type-selection, there may be a case, depending upon the direction of rotation of the type-selecting ring 1, that the rack bar 40 is lifted to release the rack 40' from engagement with the type-selecting ring gear 1, is moved to the right or left on the rollers 56 of the arms 41 and 42 and is again lowered to reset the meshing of the rack 40' with the ring 1. The numeral 57 indicates a cylinder to elevate or lower the frame for resetting the meshing engagement and the numeral 54 denotes a stop to stop the rotation of the ring 1 when the meshing is released. Since it is necessary to perform the type-selection in short time, the release and the reset of the meshing are also effected rapidly, it could result that the piston rod for the cylinder 47 be distorted or damaged due to undesirable vibration of the rack bar 40. FIGS. 21 to 23 show an apparatus to prevent such vibration.

In this aspect of the invention, grooves 43' are provided on either side of the groove of the frame 43, on which grooves 43' the protrusion 49'' of a leg on of the connecting means 49, and the protrusion of a leg type-selecting cylinder, for example, the protrusion of the leg 46'' of the cylinder 46 are fitted and slide to prevent such vibration.

When the grooves 43' of U shape are to be made on either side of the groove of the frame 43, it is advantageous to cut off the lower part 43'' of the frame 43 as shown in FIGS. 22 and 23 for ease of working.

On the left side of FIG. 21 is shown detecting means for detecting possible erroneous action in type selection, in which a rod 59 for detecting the erroneous action is provided on the tip end of the rack bar 40. Said rod has grooves 58 for generating pulses and the pitch thereof is equal to that of the rack 40'. The erroneous action in the type selection can be detected with a microswitch 60 and generating therewith the same pulses as the number of grooves passed, the microswitch 60 being actuated by contact therewith of grooves 58.

The numeral 61 denotes a detector to detect the up or down movement of the cylinder 57 and the numeral 62 denotes a detector to detect the operation of the lock of the stop means 54 for the ring 1.

FIGS. 24a and 24b together shown a block diagram of an automatic control apparatus for the type-selecting apparatus of this invention, which is described below with reference to FIG. 21.

After type-selection is over, the cylinder 57 is activated to release the rack 40' to free the ring 1. The detector 61 is caused to detect the position of the cylinder 57 after the operation. At this time the next type-selection is calculated, the rack 40' is moved over its entire stroke to the side opposite to the direction in which the next type-selection is to be conducted. Accordingly, a set given of three cylinders 45, 46 and 47 is placed under such condition that all of them are either extended or contracted to a "reset" condition.

When a signal of completion of marking is given by the marking roll, the cylinder 57 is operated to lower the frame 43, release the detector 61, allow the rack 40' to mesh with ring 1, actuate the cylinder for the stop 54 to release the lock and operate the detector 62. Under this condition, the cylinders 45, 46 and 47 are operated according to the predetermined figures calculated by the arithmetic circuit so that the rack bar 40 is moved and the rings 1 are rotated to select types. The amount selected is converted to the number of pulses obtained from the amount of movement of the rack bar 40 by means of the detecting rod 59 and the microswitch 60. After the amount of preset and that of movement are compared as to whether or not an error is existed, a signal is generated to proceed to the next process.

In the preset memory unit of FIG. 24a, the numbers, letters, figures, etc. to be marked are preset and stored by means of computer, card, tape or operator's manual operation. According to the signal N hereinafter described, the next preset value C is taken out and made the present preset value A, which is then sent together with the preceding preset value B to the comparing arithmetic circuit. The signal N is generated unless an error is detected in the type-selecting operation.

In the comparing arithmetic unit, there are two processes, one is a reset process before type-selection and the other is a type-selecting process. In the reset process, the cylinders 45, 46 and 47 are actuated for type-selection according to the signal R which is obtained when the signal for marking instruction is given under the condition that the cylinder 57 is operated and the detector 61 is working. In order to select the ring 1 having twelve teeth by the use of the rack 40' having six teeth, it is necessary to move the ring gear 1 to the right or left as far as six teeth. At the time of reset or when the ring gears 1 are released from the rack gear 40', it is necessary to reset the whole stroke corresponding to six teeth in the opposite direction so as to secure the stroke for the next type-selecting step. The judgment required therefor is based upon the following correlations, in which A is the present preset value and B is the preceding preset value.

$$\begin{aligned}
 A - B \geq 0 & \quad \begin{cases} |A - B| \geq 6 & \text{six to left} \\ |A - B| < 6 & \text{six to right} \end{cases} \\
 A - B < 0 & \quad \begin{cases} |A - B| \geq 6 & \text{six to right} \\ |A - B| < 6 & \text{six to left} \end{cases}
 \end{aligned}$$

As shown above, the subtraction of the preceding preset value B from the present preset value A is conducted, and considering the plus or minus thereof and whether the absolute value of A - B is bigger than 6, the direction is determined to right or to left whereby the entire stroke is actuated.

In FIGS. 24a and 24b is shown a circuit construction wherein when the signal R is given, the signal for 6 judges whether the reset operation is to go to right or to left according to combination of A - B and $|A - B| - 6$.

In accordance with the above operation, the step proceeds under the reset conditions until the marking is completed.

Then the cylinder 57 is actuated reversely, the ring gears 1 mesh with the rack gear 40' and the stop 54 is released from locking. At this time the signal S is generated to start type-selecting operation. In the type-selecting operation, there are relations below.

$$\begin{array}{ll} A-B \geq 0 & \begin{cases} |A-B| \geq 6 & \text{to right } 12 - |A-B| \\ |A-B| < 6 & \text{to left } |A-B| \end{cases} \\ A-B < 0 & \begin{cases} |A-B| \geq 6 & \text{to left } 12 - |A-B| \\ |A-B| < 6 & \text{to right } |A-B| \end{cases} \end{array}$$

Accordingly, in FIG. 24b, when the signal S is given, a signal for either right or left (opposite direction to reset) and either $12 - |A-B|$ or $|A-B|$ are selected based upon the $A-B \geq 0$ or $A-B < 0$ or $|A-B| \geq 6$ or $|A-B| < 6$ whereby the position of the type-selecting rings 1 can be moved from the preceding B to the present A. The signal S may be generated under the condition that the rack 40' has come into engagement with the ring 1 according to the operation of the cylinder 57 and the locking of the ring 1 has been released by the operation of the cylinder for the nail 54.

The switching to right from left or vice versa corresponds to the switching of the connections of pipes for the cylinders 45, 46 and 47, which only corresponds to the switching of the electric signal to positive or negative from the view point of electric circuit.

The calculation as set forth above can be done for shorter time than the driving apparatus hereinafter described and thus the result of it is stored in the primary memory circuit. The output circuit is explained below.

The preset value stored in the primary memory circuit is a binary number. Accordingly, in order to connect the signal to the operation of the cylinders 45, 46 and 47, a cord converting circuit is provided. Also an electric source is necessary for actuating the electromagnetic valve 52. Thus a drive amplifier is provided. In this output circuit, using the signal R at the reset time and the signal S at the set time, the signal H is generated after constant time of delay, said signal H being used to actuate the circuit.

In the drive unit, according to the instructions of the comparing arithmetic unit, the rack bar 40 is moved to right or left over the entire stroke before reset. After the reset, the cylinder 57 is caused to descend whereby the stop 54 is released so that the rack 40' meshes with, and rotates the ring gear 1. Thereafter, in accordance with the instructions of the comparing arithmetic unit, one or more of the electromagnetic valves 52 is opened to actuate one or more of the type-selecting cylinders 45, 46 and 47, elongate or shorten the length of the row

of cylinders, move the rack bar 40 to right or left, and cause the teeth of the type-selecting ring to rotate as instructed.

The indexing of the type-selecting rings 1 is completed as described above. Before the indexing of the next preset value C, it is detected whether or not there has been any erroneous action in the present indexing operation.

In the circuit for detecting any erroneous action, the 10 number of pulses generated and sent from means to detect the amount of movement of the rack mounted on the tip of the rack bar 40 is compared with the preset number sent from the primary memory circuit of the comparing arithmetic unit. If it is NO, the alarm and stop means is actuated. On the other hand, if it is YES, 15 in the case of reset time, the cylinder is actuated to allow the rack gear 40' to mesh with the ring gear 1 to proceed to the type-selecting preset process when the signal informing completion of marking comes, while in 20 the case of set time, the marking is conducted and simultaneously the cylinder 57 is actuated to release the rack gear 40' from the ring gear 1 to proceed to the reset process when the instructions for marking comes. At this time, the signal N to preset the next preset value 25 C for the present time is also generated whereby it is returned to the original condition.

Since the automatic control apparatus for the type-selecting apparatus of this invention is so composed as mentioned above, if only the input of the next preset 30 value is given as the C to the preset memory unit, the type-selecting apparatus can automatically be actuated as desired without any erroneous action.

In case that the material to be marked is a steel strip sheet, the marking position is sequentially carried at the interval of several seconds and the row of the types to be marked often amounts from several figures to 10 odd figures, which necessitates very rapid selection of types without any erroneous action. This can never be accomplished by manual operation and this invention 35 has important advantages in this respect.

FIG. 25 is a block diagram which shows the outline of the automatic control apparatus for determining the height of the marking machine; FIG. 26 is a schematic view around the marking machine.

It has heretofore been a practice for marking the material as being transported to stop the transportation of the material, effect marking under the stop condition and thereafter resume transportation of the material. Thus there has so far been no requirement for adjusting the height or position of the marking machine and such apparatus has been unknown.

However, if the marking of the material is carried out while it is being transported, there is no need of stopping the transportation of the material nor wasting time in marking. In order to carry it out it is necessary for the marking roll to effect marking while rolling on the material to be marked. However, since the thickness of the material transported is usually irregular, the marking machine must preset the thickness of the material just before marking and rapidly adjust the height or position thereof. The apparatus of this invention is particularly useful when the tip end or its vicinity of the material is to be marked.

In FIG. 25, the numeral 63 is an apparatus to detect the present height of the marking machine; the numeral 64 is an apparatus to convert said height into signals; the numeral 65 is an apparatus to detect the thickness

of the material plate to be marked; the numeral 66 is an apparatus to convert said thickness into signals; the numeral 67 is an apparatus to compare and calculate the signal for the present height of the marking machine regarding 64 and the signal for the present thickness of the material regarding 66 to thereby give instructions about the next height of the marking machine; the numeral 68 is an apparatus to detect the motor velocity according to that instruction; the numeral 69 is a control panel to control the motor velocity based upon the value detected by 68; the numeral 70 is a motor for presetting the next height of the marking machine; the numeral 72 is a brake apparatus to control the velocity of the motor 70; and the numeral 71 is an electric source for supplying power to the motor 70 and the brake apparatus 72.

In FIG. 26, the numeral 73 is a fluid operated cylinder to push the marking machine down to the material to be marked; the numeral 74 is a rolling-type eccentric marking roll having an assembly of the ring gears 1 provided with the marking punches; the numeral 7 denotes pinch rolls grasping an assembly of ring gears and guiding the rotation thereof; the numeral 75 is a material to be marked carried over the roll line 76 and approaching to the marked position along the arrow; the numeral 77 is a support roll to receive the load of the material; the numeral 79 is a threaded rod suspending the whole marking machine; the numeral 80 is a worm wheel meshing with the rod 79 in the axial center part; the numeral 81 is a worm meshing with the worm wheel 80; and the numeral 82 is a motor to rotate the worm 81 and corresponds to the motor 70 of FIG. 25.

In accordance with the instructions given by the comparing arithmetic apparatus 67 after comparing and calculating the signal for the present height of the marking machine and the signal for the thickness of the material as being transported, the motor 82 is actuated to rotate the worm 81 whereby the worm wheel is caused to rotate so as to lift or lower the whole marking machine, which results in an advantage that the marking machine can be positioned at the most appropriate height with respect to the material 75.

FIG. 27 is a block diagram showing the structure of an automatic control apparatus for the marking position and FIG. 28 is a schematic side view illustrating one embodiment of FIG. 27.

Strictly speaking, this invention relates to an automatic control apparatus for effecting automatic marking with accuracy on the material as being transported at the designated position, said material being sequentially transported with irregular speeds and irregular intervals.

In said FIGS. 27 and 28, 84 is an apparatus for generating a signal informing that the tip end of the material 75 has passed the photo-electric switch 83; 78 is an apparatus for generating a pulse each time the line roll 76 rotates by a predetermined length; 85 is an apparatus for presetting the respective marking distances $l_1, l_2, \dots, l_n$ from the tip end of the long material 75 as being sequentially transported and giving instructions to a control apparatus 86; said control apparatus 86 is intended to store the distance L of the photo-electric switch provided ahead of the axial center of the pinch rolls and the value obtained by subtracting the πr of the pinch roll from the sum of said $l_1, l_2, \dots, l_n$, calculate the number of pulses of 78 from the time when the signal of 84 is received to thereby calculate the time when the

marking roll 74 comes into contact with the material 75; and give instructions to start the marking machine at each time. The marking roll 74 is eccentrically pinched by the pinch rolls 7 such that many ring gears 1 are assembled, and the marking punches 2 to be marked with next time are arranged to be in a line on the uppermost position at each that time. Therefore, in half rotation after the pinch rolls 7 comes into contact with the material 75, accurate marking takes place in order.

In the operation of the apparatus shown in FIGS. 27 and 28, if only the marking distances $l_1, l_2, \dots, l_n$ from the tip end of the strip material transported at a given time are given as input to the instructing apparatus 85, the whole apparatus is automatically actuated to effect marking on each designated position with great accuracy.

As set forth hereinbefore in detail, this invention has unique advantages that the material can be marked while it is being transported without stop, and that the marking punches provided with numbers, letters, figures and so on to be marked which may be varied each time can be selected rapidly and accurately so that the marking can be effected on each designated line.

As to the power to be used in this invention, all the references to 19 of FIG. 12 and 82 of FIG. 26 are all defined as electric power by way of explanation, but they can of course be fluid pressure and the like.

As to the structure, the projected rings 34 and 36 of FIGS. 13 to 16 should not be limited to three-fold.

Any changes and modifications can thus be made without departing from the spirit of the invention.

FIGS. 29 to 31 illustrate one embodiment of the marking mechanism of this invention in which FIG. 29 is a front view, FIG. 30 is a partly enlarged front view and FIG. 31 is a partly enlarged side view thereof, although this invention should not be limited to this mode of working.

The numeral 76 is a line roll as also shown in FIG. 26 and FIG. 28; 77 is a backup roll; 19, 20, 22 and 23, and 30 are the driving means, brake means, one position clutch and marking roll shown in FIG. 12, respectively; 1 is the type-selecting ring gear; 2 is the tooth through which the marking punch has been inserted; 40', 40, 41 and 42, 43, 45 to 47, and 49 are the rack, rack bar, rack bar arm, frame, type-selecting fluid cylinders, and connecting means shown in FIGS. 18, 19 and 21, respectively; 4, 6, and 7 are the rotatable shaft for the marking roll, the housing for the bearing, and the pinch rolls for the marking roll shown in FIGS. 1 and 2; 73, 79, and 82 are the cylinder for lifting or lowering the marking roll, threaded rod and motor shown in FIG. 26.

In this example, automatic control is effected so as to automatically stop the apparatus at any desired angle by means of the drive means 19, the velocity reduction means 89, the brake means 20, the primary and secondary one position clutch 22 and 23, and the free connecting rod 90. The marking punch 2 is set on each tooth of the type-selecting ring gear 1 which are overlapped by the numbers corresponding to figures to be marked. With these ring gears, the marking roll 30 rolls while pinched by the pinch rolls 7. The roll 30 is pivotally supported via the rotatable shaft 4 on the inverted U-shape housing 7. The housing 7 is pivotally attached by the tip end of the arm to the shaft 51', and it is lifted or lowered suspended by the fluid cylinder 73 while preventing the fluctuation in the axial direction of the

roll 30. The upper end of the cylinder 73 is pivoted to one end of a lever 98 whereby it is lifted or lowered. The other end of the lever 98 meshes with the threaded rod 79 which is pivoted to the shaft 97 and rotates by means of the motor 82.

The shaft 97 thus suspending the whole marking apparatus is mounted on a pair of longitudinal beams 93, 93, which beams are in turn fixed to a pair of the above lateral beams 94, 94 and suspended therefrom to guide the up and down movement of the inverted U-shape housing 7. Said lateral beams 94, 94 constitute a box shape supported by poles 95, 96 standing on either side of the roll line.

In this example, the frame 43 mounts on its underside the arms 41, 42 supporting the rack bar 40 with the rack 40' and on its upper side a group of the cylinders for type-selecting 45, 46 and 47. It is mounted on a pair of arms 99, 100 suspending from said beams 93 and does not move up or down but the ring gears 1 of the marking roll 30 moves up and down as described above. This structure is the reverse of that shown in FIGS. 18, 19 and 21 but the technical idea is the same. Thus in the case of said FIGS., the frame is elevated to lift the rack 40' and release it from meshing with the ring gears 1 to move the rack bar 40 for type-selecting; and in the type-selecting the frame 43 is caused to descend to resume meshing and the rack bar is caused to move to rotate the ring gear. However, it is essentially necessary that the marking roll is lifted or lowered at each time for marking but such is not necessary about the rack. Therefore, the structure of this example does not cause trouble.

In this example, in accordance with the practice shown in FIGS. 27 and 28, a plurality of values regarding the marking positions of the material transported this time and the combination of the marking punches is received as input by the automatic control apparatus, and the first marking position and type-selecting are completed. When the material is transported on the line rolls, the thickness of the material is detected according to the method of FIGS. 25 and 26 to preset the height of the marking roll. In the meantime the movement of the rack is completed for the next type-selecting since the rack is being released from meshing with the ring gear. When the material reaches a predetermined transport position, the marking roll is brought into contact with the surface of the material at the designated angle according to the instructions and, at the same time, in order to secure marking the fluid cylinder is actuated to allow the marking roll to rotate on the surface of the material while pushing said surface. When the marking is completed, said roll is lifted to allow the ring gear to mesh with the rack and according to the instructions of the automatic control apparatus the rack bar is caused to move to complete type-selecting so as to be ready for the next marking operation.

When the apparatus of this example is used, only the input of the marking positions and the combination of the punches to the automatic control apparatus can effect marking with automatic control without any obstacle to the transportation of the material to be marked.

We claim:

1. Apparatus for marking indicia on a plate moving along a fixed path which comprises

a marking roll including an elongated central shaft having opposed ends, a plurality of toothed rings

loosely mounted on said central shaft, the teeth on each of said rings carrying indicia punch means projecting from the outer periphery of said rings, rotatable shaft means fixed to said central shaft and extending longitudinally from the opposite ends of said central shaft,

means for supporting said rotatable shaft means for rotation about a fixed axis,

means selectively engageable with the teeth on each of said rings for rotating each of said rings upon said central shaft to preset positions to align a selected tooth on each ring with selected ones on the others of said rings and thus present a desired line of punch indicia to be marked on said plate,

means for selectively locking said rings and a preset line of punch indicia carried thereby to said central shaft for rotative movement therewith, and

a pair of pinch rolls mounted concentrically on said rotatable shaft means for rotation therewith, the diameter of said pinch rolls being greater than that of said rings, the axis of said central shaft being disposed eccentrically of the axis of said fixed axis by a distance equal to one-half of the difference between the diameter of said pinch rolls and said rings whereby when said rings are locked to said central shaft and said rotatable shaft means is rotated only the preset line of punch indicia carried on said rings projects radially beyond the peripheral expanse of said pinch rolls for effecting marking on a plate moving in rolling contact with said pinch rolls.

the means for locking said rings to said central shaft comprising a locking member received in a groove in the outer surface of said central shaft, the inner circumferential surface of each of said rings being provided with notches, said locking member and said groove being provided with companion oblique surfaces, sliding of said member longitudinally of said groove in one direction being operative to urge at least a part of said locking member into locking engagement with the notches in each of said rings, sliding of said locking member in an opposite direction being effective to retract said locking member wholly within said groove.

2. Apparatus for marking indicia on a plate moving along a fixed path which comprises

a marking roll including an elongated central shaft having opposed ends, a plurality of toothed rings loosely mounted on said central shaft, the teeth on each of said rings carrying indicia punch means projecting from the outer periphery of said rings, rotatable shaft means fixed to said central shaft and extending longitudinally from the opposite ends of said central shaft,

means for supporting said rotatable shaft means for rotation about a fixed axis,

means selectively engageable with the teeth on each of said rings for rotating each of said rings upon said central shaft to preset positions to align a selected tooth on each ring with selected ones on the others of said rings and thus present a desired line of punch indicia to be marked on said plate,

means for selectively locking said rings and a preset line of punch indicia carried thereby to said central shaft for rotative movement therewith, and

a pair of pinch rolls mounted concentrically on said rotatable shaft means for rotation therewith, the

diameter of said pinch rolls being greater than that of said rings, the axis of said central shaft being disposed eccentrically of the axis of said fixed axis by a distance equal to one-half of the difference between the diameter of said pinch rolls and said rings whereby when said rings are locked to said central shaft and said rotatable shaft means is rotated only the preset line of punch indicia carried on said rings projects radially beyond the peripheral expanse of said pinch rolls for effecting marking on a plate moving in rolling contact with said pinch rolls.

the teeth on each of said rings being provided with a radial passage, there being a marking punch received in said passage, a tip end of said punch being disposed at the outer periphery of the associated tooth, said tip end carrying an arcuate marking surface, the radius of said marking surface being smaller than that of a circle circumscribed by the peripheries of the teeth on said ring, there being a pin passing axially through each tooth and the punch received therein to secure such punch to its associated tooth, said apparatus

further comprising a device for stopping the marking roll including a primary one-position clutch idly mounted on said rotatable shaft means and having the teeth of a worm wheel on the outer circumferential surface thereof, a secondary one-position clutch slidably carried on said rotatable shaft means, a worm meshing with said worm wheel for rotatably positioning said one-position clutch a desired angle of rotation of the same and for thereafter holding said clutch locked in said rotated position, brake means to control the rotation of said rotatable shaft means, control means for opening and closing circuitry operating the primary one-position clutch means and brake means, respectively, and means for directing operation of said control means.

3. Apparatus for marking indicia on a plate moving along a fixed path which comprises

a marking roll including an elongated central shaft having opposed ends, a plurality of toothed rings loosely mounted on said central shaft, the teeth on each of said rings carrying indicia punch means projecting from the outer periphery of said rings, rotatable shaft means fixed to said central shaft and extending longitudinally from the opposite ends of said central shaft,

means for supporting said rotatable shaft means for rotation about a fixed axis,

means selectively engageable with the teeth on each of said rings for rotating each of said rings upon said central shaft to preset positions to align a selected tooth on each ring with selected ones on the others of said rings and thus present a desired line of punch indicia to be marked on said plate, means for selectively locking said rings and a preset line of punch indicia carried thereby to said central shaft for rotative movement therewith, and

a pair of pinch rolls mounted concentrically on said rotatable shaft means for rotation therewith, the diameter of said pinch rolls being greater than that of said rings, the axis of said central shaft being disposed eccentrically of the axis of said fixed axis by a distance equal to one-half of the difference between the diameter of said pinch rolls and said

rings whereby when said rings are locked to said central shaft and said rotatable shaft means is rotated only the preset line of punch indicia carried on said rings projects radially beyond the peripheral expanse of said pinch rolls for effecting marking on a plate moving in rolling contact with said pinch rolls,

the means for rotating each of said rings upon said central shaft comprising a corresponding plurality of rack bars associated one with each of said rings, means for guiding and supporting the rack bars for sliding travel, movement means to slide said rack bars, said movement means including a plurality of fluid cylinders connected in series, the cylinders being operative to extend or retract the piston rods thereof upon direction from a control unit to move the respective rack bars connected to the piston rod ends for a desired distance, means for moving the rack bars into and out of mesh with the teeth on said rings, said rack bars having teeth corresponding in number to those on the ring gears, automatic control means for directing the operation of said movement means to arrange said rack bars in a desired position suitable for the next rotation of said rings preliminary to marking and give said movement means direction to obtain a desired ring positioning by combination of cylinders having different strokes when the teeth of the rings mesh with the racks after marking is completed, the plurality of cylinders being arranged at both sides of a beam standing on the upper surface of a strand such that they are staggered by half the plane width, the row of rack bars meshing with the row of said ring gears being mounted on guide rollers and supported by an arm, the ends of the piston rods of each cylinder and the ends of the rack bars being connected by connecting means passing through the stand, a plurality of dovetail grooves being provided on the stand common for said cylinders and said rack bars, protrusions being provided on each side of said connecting means, and each said protrusion being receivable in a dovetail groove.

4. The apparatus of claim 3 further comprising a preset memory unit for making the present preset value A for marking character from the next preset value C for marking character and storing the same with the preceding preset value B for marking character, a comparing arithmetic circuit which compares the present preset value A for marking character with the preceding preset value B so as to calculate (a) the value by which a ring should be rotated clock-wise or counter-clockwise within the range less than half of the number of the teeth and (b) the direction in which the associated rack bar should be moved and reset by the distance corresponding to half of the number of the teeth of the ring gear and stores the same, an output circuit to convert the calculated values into the normal figures and amplify the same for driving, driving means to open an instructed electromagnetic valve to operate an associated cylinder so that the rack bar may be moved to right or left by the distance as instructed, and means for detecting any erroneous operation which compares the amount of movement of the rack bar sent from means for detecting the amount of the movement of the rack bar with the instruction figures sent from the comparing arithmetic circuit.

5. The apparatus of claim 4 in which said marking roll is supported for vertical upward and downward movement relative to the fixed travel path of said plate, said apparatus further comprising device for adjusting the height of the marking roll relative to said travel path, said device comprising means to detect the present height of the position of the marking roll, means to convert said height into signals, means to preset the thickness of the material plate to be marked, means to convert said thickness to a signal, means to compare and calculate said two signals received as input and thereby give the instruction signal for velocity to the motor depending upon the deviation of the distance between the present position and the next position of the marking roll so that said roll may move to the next position, said motor being operated to raise and lower said marking roll, a control panel to control the motor velocity, and means for supplying power to said motor.

6. The apparatus of claim 5 further comprising an automatic control for the marking position of the marking
